(57) **CLAIM**

The ornamental design for a twist-up snack dispenser, as shown and described.

DESCRIPTION

FIG. 1 is a front-top perspective view of a twist-up snack dispenser in a closed configuration according to my new design;

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is a bottom view thereof;

FIG. 8 is a front-top perspective view of the twist-up snack dispenser of FIGS. 1 to 7, shown in an exploded configuration according to my new design;

FIG. 9 is a front-top perspective view of the twist-up snack dispenser of FIGS. 1 to 8, shown in an open configuration according to my new design;

FIG. 10 is a front view thereof;

FIG. 11 is a rear view thereof;

FIG. 12 is a right-side view thereof;

FIG. 13 is a left-side view thereof;

FIG. 14 is a top view thereof; and,

FIG. 15 is a bottom view thereof.

The broken lines in the drawing depict portions of the twist-up snack dispenser that form no portion of the claimed design.
